UNITED STATES PATENT OFFICE

2,000,844

LOOSE LEAF BINDER

Stanley G. Johnson, Grosse Pointe, Mich., assignor to The Burkhardt Company, a corporation of Michigan

Application May 9, 1934; Serial No. 724,701

7 Claims. (Cl. 129—13)

This invention relates to loose leaf binders of the post type and is applicable to both closed back and open back binders.

The main object of this invention is to provide a sturdy inexpensive binder of such construction that the leaf-engaging members may be positively retained in compressed or any desired relation to each other.

Another object of this invention is to provide a loose leaf binder having post type locking devices secured to one of the leaf-engaging members capable of positively retaining cooperating posts secured to the other leaf-engaging member in telescopic relation thereto and thereby positively holding the said leaf-engaging members in compressed or any desired relation to each other.

Another object of this invention is to provide a positive locking post type loose leaf binder which may be economically but sturdy constructed with screw machined post type locking device parts as distinguished from the usual well known stamped guides and slides which may be easily bent out of alignment during use.

And still another object of this invention is to provide a positive preferably double detent type engagement between the cooperating parts of the locking devices which hold the leaf-engaging members of a loose leaf binder in the desired relation to each other as distinguished from the usual frictional type locking devices or devices relying upon a vise-like biting engagement between the cooperating parts thereof.

Illustrative embodiments of this invention as applied to closed back binders are shown in the accompanying drawing, in which:

Fig. 1 is a view in perspective having portions of the binder broken away showing a loose leaf binder of a construction embodying the invention.

Fig. 2 is an enlarged transverse section of Fig. 1 showing the binder unlocked and the cooperating parts of the binder and locking device disengaged.

Fig. 3 is an enlarged cross sectional view similar to Fig. 2 except that the binder is in a locked position and the cooperating parts of the binder and locking device are shown engaged.

Fig. 4 is a vertical section taken on line 4—4 of Fig. 2.

Fig. 5 is a vertical section taken on line 5—5 of Fig. 3.

Fig. 6 is a sectional view taken on line 6—6 of Fig. 3 looking in the direction indicated by the arrows.

Fig. 7 is a detailed view in perspective showing the engagement between the cooperating parts of the locking device.

Fig. 8 is a sectional view similar to Fig. 6 except that it shows another embodiment of my invention.

In the embodiment of the invention shown in Figs. 1 to 7 inclusive of the drawing the loose leaf binder comprises two leaf-engaging members 10 and 11 disposed in opposite relation to each other, 10 covers 12 and 13 flexibly connected or hinged to the said leaf-engaging members, solid and hollow posts 14 and 15 on leaf-engaging members 10 and 11 respectively capable of receiving punched filler sheets 16 by means of properly spaced holes 15 therein, and two hollow post type locking devices having preferably hardened solid grooved posts 17 on one of the leaf-engaging members 10 and hollow posts 18 on the other leaf-engaging member 11.

The solid and hollow posts 14, 15, 17 and 18 may be arranged in any desirable staggered relation with respect to the leaf-engaging members 10 and 11. The leaf-engaging members 10 and 11 are each preferably formed of sheet metal in the shape of an L to provide a closed back for the binder. However, they may each comprise simply a flat sheet of metal for the open back type of binder. The leaf-engaging members, covers, flexible cover connections or hinges and covering for the same may be of any desired construction and material known in the book-binding art.

This invention consists of a novel means for positively locking the leaf-engaging members of a post type loose leaf binder in a compressed or any other desired relation to each other within the useful limits of the telescoping engagement of the solid and hollow posts thereof. The locking means relies upon a detent type engagement between the cooperating parts of the locking device.

The said locking device consists of a round solid peripherally grooved post 17 preferably having an upset and shouldered hollow end forming a rivet 19 for securing the said post to the leaf-engaging member 10, the said solid grooved post 17 being preferably identical in size to solid posts 14. A hollow post 18 having an internal diameter slightly larger than solid grooved post 17 is preferably shouldered to form a rivet 20 for securing the same to the leaf-engaging member 11, the said hollow post 18 being preferably equal in height and internal diameter to hollow posts 15. Solid posts 14 and 17 are riveted or otherwise

secured to the leaf-engaging member 10 at such spacing that they will register with and be telescopingly engaged by hollow posts 15 and 18 which are riveted or otherwise secured to the 5 leaf-engaging member 11.

The hollow posts 18 are preferably formed by 10 drilling an eccentrically located vertical hole slightly larger in diameter than the solid posts 17 through a round blank of the proper length, flattening the remaining thick wall of the post to 15 form a flat side of the said post 18 as shown in Fig. 1, and shouldering the same to form a hollow rivet at the bottom thereof as hereinbefore described.

15 Now referring to Fig. 6, each hollow post 18 is provided with a horizontally disposed round hole 21 drilled normal to the flat side of and partly through the hollow post 18 and on the same center as a smaller hole 22 which forms a shoulder 20 23 to seat a preferably hardened rivet 24 which functions to lock the solid grooved post 17 against movement relative to the hollow post 18 when 25 telescopingly engaged thereby.

The rivet 24 is formed with a shoulder beneath 25 the head 25 to abut against the shoulder 23 formed in the hollow post 18. The rivet head 25 is of slightly less diameter than the hole 21 to permit assembly and the free rotation of the rivet 24. The top of the rivet head 25 is ground 30 before hardening to form a concaved groove having substantially the same radius as the vertical hole in the hollow post 18. The shank of the rivet 24 is long enough to extend through the hole 22 in the hollow post 18, receive a spring washer 35 26, be flattened on two sides to provide a key 29 to engage an operating lever 30, and form a head to retain the said rivet, spring washer and operating lever in the desired position in relation to the said hollow post 18.

40 The rivet 24 may be tapered instead of shouldered without departing from the broad invention described herein, in which case holes 21 and 22 of the hollow post 18 would be formed as one tapered hole.

45 The operating lever 30 is provided with a lug 31 to abut against the hollow post 18 when the concaved rivet head 25 is in a disengaged position in relation to the solid grooved post 17 as shown in Fig. 2 and Fig. 4.

50 In operating the embodiment of this invention as illustrated in the drawing, the punched filler sheets 16 are inserted in the binder in registry with hollow posts 15 as shown in Fig. 1. The sheets 16 as indicated by the dotted lines in Fig. 2 55 may be stacked higher than hollow posts 15 and as high as desired within the useful limits of the telescoping engagement of the solid grooved and hollow posts 17 and 18 of the locking devices.

The operating lever 30 is moved to the disengaged position shown in Fig. 2, the solid posts 14 and 17 are then brought in telescopic engagement with the hollow posts 15 and 18 respectively, the leaf-engaging members 10 and 11 are then preferably pressed into compressed relationship 60 to each other thereby engaging the punched filler sheets 16 as in Fig. 3 and the operating lever 30 is moved to the engaged position as shown in Fig. 3 to lock the leaf-engaging members 10 and 11 in the desired relation to each other.

65 The positive locking means of engagement between the solid grooved and hollow posts 17 and 18 is accomplished by the preferably double detent engagement therebetween as illustrated in Figs. 4, 5 and 7. Fig. 4 shows the solid grooved and hollow posts 17 and 18 in unlocked relation

to each other with the operating lever 30 in a disengaged position and the grooved head of the rivet 24 coincident with the inner surface of the hollow post 18. When the operating lever 30 is moved toward its engaged position it causes the grooved head of the rivet 24 to turn thereby urging the grooved solid post 17 against the inside of the hollow post 18 as indicated in Fig. 5; and by using the inside of the hollow post 18 to react against, a slight additional pressure on the operating lever 30 causes the high portions of the grooved head 25 of the rivet 24 to register with the nearest peripheral grooves in the solid grooved post 17 thereby completing the positive double detent type locking engagement between the solid 10 grooved and hollow posts 17 and 18.

15 Fig. 8 illustrates another embodiment of this invention which is identical to the loose leaf binder shown in Figs. 1 to 7 inclusive of the drawing except that the peripherally grooved solid 20 posts 17 have been replaced by the deeply knurled round solid posts 170 preferably having an upset and shouldered hollow end forming a rivet 190 for securing the said posts to the leaf-engaging member 10. The said solid posts 170 are knurled 25 in such a manner that the high portions of the grooved head 25 of the rivet 24 will register with the knurling in the solid posts 170 when the said rivet is turned into its engaged position by the operating lever 30.

30 It is readily observed that the above described binder is simple to operate, sturdy in construction and economical to manufacture, and provides an absolutely positive means for maintaining the leaf-engaging members in any desired relation to 35 each other. The grooves in solid posts 17 or the knurling of solid posts 170 may be of a wide range of detail to permit the high portions of the grooved head 25 of the rivet 24 to register therewith. Also, a single detent type locking engagement may be used by forming the rivet head 25 of the rivet 24 in the shape of an L instead of the U shaped groove as illustrated in the drawing.

40 Although only two embodiments of this invention have been illustrated and described, it will 45 be apparent to those skilled in the art that various modifications may be made therein without departing from the scope of the appended claims.

I claim:

1. A loose leaf binder of the post type comprising 50 opposed leaf-engaging members, means on said leaf-engaging members to cooperate with punched filler sheets, solid grooved posts secured to one of the leaf-engaging members, hollow posts secured to the other leaf-engaging member, adapted to telescopingly cooperate with the solid grooved posts, locking means rotatably mounted in the said hollow posts each comprising a rivet having its head concaved substantially the same radius as the center of the hollow post, and means to rotate the said rivet to urge the solid grooved post against the inside of the hollow post and cause the high portions of the grooved rivet head to register with the said solid grooved post.

2. A loose leaf binder comprising leaf-engaging members, means on said leaf-engaging members for receiving punched filler sheets, solid grooved posts secured to one of the leaf-engaging members, cooperating hollow posts secured to the other leaf-engaging member, a rivet rotatably mounted in each of the said hollow posts having its head concaved substantially the same radius as the center of the said hollow post, means to rotate the rivet in one direction to urge the solid grooved post against the inside of the hollow post and

cause the high portions of the grooved rivet head to register with said solid grooved post, and means to limit the rotation of the rivet in the other direction to bring the concaved portion of its head in axial alignment with the said hollow post to permit free reciprocating movement of the solid grooved post within the said hollow post.

5. A loose leaf binder comprising leaf-engaging members, means on said leaf-engaging members for receiving punched filler sheets, solid knurled posts secured to one of the leaf-engaging members, cooperating hollow posts secured to the other leaf-engaging member, a rotatable locking device within each of said hollow posts disposed 10 and rotatable on an axis normal thereto, and inwardly disposed detents formed on each rotatable locking device adapted to prevent relative movement of solid knurled and hollow posts by engagement with the grooves formed by the knurling of 15 the said solid knurled posts.

6. A loose leaf binder comprising opposed leaf-engaging members, means on said leaf-engaging members to cooperate with punched filler sheets, solid annularly grooved round posts secured to 20 one of the leaf-engaging members, hollow posts secured to the other leaf-engaging member telescopingly receiving the said solid grooved posts, rotatable locking means within and normal to 25 said hollow posts adapted to be urged manually into registry with said solid grooved posts.

7. A loose leaf binder comprising leaf-engaging members, means on said leaf-engaging members for receiving punched filler sheets, solid annular-

ly grooved round posts secured to one of the leaf-engaging members, cooperating hollow posts secured to the other leaf-engaging member, and rotatable locking devices within said hollow posts disposed normal thereto adapted to prevent relative movement of said solid grooved and hollow posts by registering with the solid grooved posts.

5. In a post type loose leaf binder having opposed leaf-engaging members and means for receiving filler sheets, solid annularly grooved 10 round posts secured to one of the leaf-engaging members, hollow posts telescopingly receiving said solid grooved posts secured to the other leaf-engaging member, rotatable locking devices within 15 said hollow posts disposed normal thereto, and means to rotate said locking devices into registry with the annular grooves in the solid grooved posts.

7. A loose leaf binder comprising leaf-engaging members, means on said leaf-engaging members 20 for receiving punched filler sheets, solid annularly grooved round posts secured to one of the leaf-engaging members, cooperating hollow posts secured to the other leaf-engaging member, a rotatable locking device within each of said 25 hollow posts having inwardly disposed detents formed thereon adapted to register with annular grooves in said solid grooved posts to prevent relative movement of said solid grooved and hollow posts, and means to cause rotation of said locking 30 device on an axis normal to said solid grooved and hollow posts.

STANLEY G. JOHNSON.
